US00D743376S

(12) **United States Design Patent**
Kim

(10) **Patent No.:** US D743,376 S
(45) **Date of Patent:** ** Nov. 17, 2015

(54) **SPEAKER**

(71) Applicant: **LG ELECTRONICS INC.**, Seoul (KR)

(72) Inventor: **Junki Kim**, Seoul (KR)

(73) Assignee: **LG Electronics Inc.**, Seoul (KR)

(**) Term: **14 Years**

(21) Appl. No.: **29/477,664**

(22) Filed: **Dec. 24, 2013**

(30) **Foreign Application Priority Data**

Jun. 25, 2013 (KR) 30-2013-0032736

(57) **CLAIM**

The ornamental design for a speaker, as shown and described.

DESCRIPTION

FIG. 1 is a perspective view of a speaker showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image;

FIG. 6 is a reference view thereof showing the part of this speaker which is consisted of transparent material by hatching;

FIG. 7 is an enlarged view taken along line 1-1'; and,

FIG. 8 is a reference view showing an example of the usage of the subject design.

The broken lines are for illustrative purposes only and form no part of the claimed design.

1 Claim, 8 Drawing Sheets
